UNITED STATES PATENT OFFICE.

KENNETH ROBINSON HEMMERLY, OF SOUTH BETHLEHEM, PENNSYLVANIA.

SUPPORTING STRUCTURE.

1,308,419.

Specification of Letters Patent.

Patented July 1, 1919.

Application filed September 30, 1918. Serial No. 256,199.

To all whom it may concern:

Be it known that I, KENNETH R. HEMMERLY, a citizen of the United States, resident at South Bethlehem, in the county of 5 Northampton and State of Pennsylvania, have invented certain new and useful Improvements in Supporting Structures, of which the following is a specification.

One object of my invention is to provide 10 means whereby awnings or other articles can be securely attached to supports such, for example, as stone or stucco posts.

Another object is to make my invention of 15 a strong and durable construction and so 15 that it can be easily and quickly assembled and secured in position.

A further object is to so construct my invention that it can be used as a hinge support for awnings where it is necessary to 20 attach said awnings to stone or stucco posts, walls, or partitions where it is impossible to gain access to the inside portion thereof.

These objects and other advantageous ends 25 which will be described hereinafter, I attain in the following manner, reference being had to the accompanying drawings in which

Figure 1 is a front elevation of my invention, and

Fig. 2 is a sectional view taken on the line 30 2—2 of Fig. 1.

Referring to the drawings, 3 represents a support such, for example, as a stone, cement, or stucco hollow post, wall, or partition in which 4 represents the inner surface 35 face and 5 represents the outer surface.

The support 3 has a hole 6 extending therethrough and this hole can be formed by drilling through the support and serves for a purpose hereinafter described.

40 A securing member 7, in the present instance illustrated as a one-piece hinge plate, has two oppositely disposed end portions 7^a and 7^b which are wider than the central or connecting portion 8. The central portion 8 has two hinge connecting ears 9 projecting outwardly therefrom and are provided with alined holes 10. These holes 10 form the hinge connection for example for an awning rod 11 and said rod 11 and ears 9 are pivotally connected by a pivot pin or bolt 12.

The distance between the portions 7^a and 7^b of the hinge plate 7, as is obvious from the drawings, is greater than the height of the hole 6 so that said end portions overlap 55 the top and bottom of the hole 6.

The securing plate 7 has holes 13 and 14

above and below the central portion 8. Bolts 15 and 16 respectively pass through these holes 13 and 14 and through the hole 6 in the support 3. These bolts have toggle fingers 17 in screw threaded engagement with the inner threaded ends of the bolts and of such length that when they are turned into the position clearly shown in Fig. 1 their opposite end portions will engage the inner 65 surface 4 of the support 3 at the opposite sides of the hole 6.

The hole 6 is of such width that after the plate 7 has been placed against the outer surface 5 of the support 3, room is provided at 70 either side of the central portion 8 as indicated by the reference numeral 19 to permit a workman to insert his fingers to hold the toggle fingers 17 in the above mentioned position while the bolts 15 and 16 are inserted 75 through the plate 7 and through the hole 6 after which the bolts can be screwed through the fingers 17 and in so doing will tend to relatively move the toggle fingers 17 and securing plate 7 together to clamp the support 3 between them.

The rear surface of the securing plate 7 is provided with pointed lugs 18 which, when the bolts 15 and 16 are screwed up, will engage the outer surface 5 and pierce the same, 85 as clearly shown in Fig. 2. By this means the securing plate 7 will be prevented from accidentally moving in a lateral direction during its application to the support 3.

If desired, after the plate 7 has been secured as above noted, the exposed portions 19 of the hole 6 can be filled with cement or similar substance. By the above arrangement and construction of parts, the securing plate will be firmly held to the support 3 95 and will withstand great weight or tension without becoming loose or breaking said support or the adjacent parts.

While I have described my invention as taking a particular form, it will be understood that the various parts of my invention may be changed without departing from the spirit thereof, and hence I do not limit myself to the precise construction set forth, but consider that I am at liberty to make such 105 changes and alterations as fairly come within the scope of the appended claims.

Having thus described my invention, what I claim as new and desire to secure by Letters Patent is:

1. The combination of a support having a hole extending therethrough from its outer

to its inner surface; and a supporting member adapted to be placed against the front surface of said support and having toggle bolts extending through said hole in the support, said hole in the support being of less length but of greater width than that of said member to permit the toggles of said bolts to be moved to span said hole and engage the inner surface of said support 5 whereby said member is held to the support, substantially as described.

2. The combination of a support having a hole extending therethrough from its outer to its inner surface; and a supporting member adapted to be placed against the front surface of said support and having toggle bolts extending through said hole in the support, said hole in the support being of less length but of greater width than that of said member to permit the toggles of said bolts to be moved to span said hole and engage the inner surface of said support whereby said member is held to the support, said member having pointed lugs thereon adapted 15 to pierce the outer surface of said support and prevent accidental movement of the member, substantially as described.

3. The combination of a support having a hole extending therethrough from its outer to its inner surface; and a solid one-piece hinge adapted to be placed against the front 20

surface of said support and having toggle bolts extending through said hole in the support, said hole in the support being of less length but of greater width than that of 35 said hinge to permit the toggles of said bolts to be moved to span said hole and engage the inner surface of said support whereby said hinge is held to the support, substantially as described.

4. The combination of a support having a hole extending therethrough from its outer to its inner surface; and a hinge having a relatively narrow central portion and adapted to be placed against the outer surface of 40 said support and having toggle bolts extending through said hole in the support, said hole in the support being of less length than said hinge but of greater width than the width of said relatively narrow portion of 45 said hinge to permit the toggles of said bolts to be moved to span said hole and engage the inner surface of said support whereby said hinge is held to the support, substantially as described.

55 In testimony whereof I have signed my name to this specification in the presence of two subscribing witnesses.

KENNETH ROBINSON HEMMERLY.
